UNITED STATES PATENT OFFICE.

THOMAS F. CARR, OF WILMINGTON, DELAWARE.

DESIGN FOR A PATRIOTIC FRAME.

52,634.

Specification for Design.

Patented Nov. 12, 1918.

Application filed April 23, 1918. Serial No. 230,348. Term of patent 3½ years.

To all whom it may concern:

Be it known that I, THOMAS F. CARR, a citizen of the United States, residing at Wilmington, in the county of New Castle and State of Delaware, have invented a new, original, and ornamental Design for a Patriotic Frame, of which the following is a specification, reference being had to the accompanying drawing, forming a part thereof.

The figure is a front elevation of a patriotic frame showing my new design.

I claim:

The ornamental design for a patriotic frame, as shown.

THOMAS F. CARR.
